UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI.

WEATHER STRIP.

Application filed March 3, 1922. Serial No. 540,694.

To all whom it may concern:

Be it known that I, ALFRED M. LANE, a citizen of the United States, and a resident of the city of St. Louis and State of Missouri, have invented a new and useful Improvement in Weather Strips, of which the following is a specification.

My invention relates to weather strips.

Heretofore there has been great difficulty in weather-proofing door sills and hinged window sills, due partly to the fact that storm water naturally accumulates to a greater or less extent on such sills and is blown through the crack beneath the door or window, and partly also to the fact that water flowing down the side of the frame may be delivered onto the sill back of the sill weather strip. The principal object of the present invention is to overcome this difficulty; and it consists principally in correlating the side strips with the bottom strip so that the side strips are located outwardly beyond the bottom strip; and it also consists in equipping the sill with a member comprising an upper strip that is relatively rigid and a lower strip that is resilient, and in equipping the door or sash with a strip adapted to pass between said rigid sill strip and the resilient sill strip beneath the same. It also consists in the arrangement last-mentioned together with weep holes or outlets for delivering the water outwardly from the engaging strips; it also consists in the arrangement above described together with a wind break on the outer or exposed side of the device; it also consists in the arrangements and combinations of parts hereinafter described and claimed.

In the accompanying drawing, wherein like symbols refer to like parts wherever they occur,

Fig. 1 is a horizontal cross-section taken through a casement window showing my invention applied thereto, the sash being shown in closed position;

Fig. 2 is a similar section through the hinged side of said window, the sash being shown in opened position.

Fig. 3 is a fragmentary vertical cross-section through the lower portion of the window, the sash being shown in closed position and one side of the window frame being shown in elevation;

Fig. 4 is a horizontal cross-section simi-

lar to Fig. 2, showing a modified form of side strip;

Fig. 5 is a vertical cross-section similar to Fig. 3, showing sill members of modified form;

Fig. 5^a is a similar view, showing the position of the flexible sill strip when the closure is in the open position; and

Figs. 6, 7, 8, 9 and 10 are views similar to Fig. 3, showing sill members of modified form.

Referring to the construction illustrated in Figs. 1 to 3, the sill member comprises a relatively rigid strip 11 and a relatively flexible strip 12. The rigid strip is offset to form a Z section and the outer margin or flange thereof is fastened to the sill A while the inner margin is raised above the sill and the middle web portion that connects the two flanges is vertically disposed and provided with weep holes or outlets 11^a 75 near the lower flange. The resilient strip 12 has a flat horizontal portion that rests on the sill underneath the outer flange of the rigid strip, while the inner portion of said flexible strip is curled upwardly and backwardly on itself underneath the inner flange of the rigid strip so as to form a resilient hollow bead adapted for yieldable engagement with the under surface of said inner flange when the sash is in the open position. 85

Cooperating with the sill member is the sash member, which is made in the form of a relatively flexible flat strip 13, whose body portion slopes upwardly on each side of its middle to form a line contact with the rigid 90 sill member and whose inner margin is rebent on the underside to form a loop or undercut groove or pocket 13^a. The outer margin of this sash strip is stiffened by a sharp rebend and is secured to the bottom 95 of the casement sash or door B at such height that the swinging of the sash will cause the edge of the rigid sill strip 11 to enter said loop. The free edge of the loop is positioned to enter between the inner 100 flange of the rigid sill strip 11 and the resilient hollow bead 12^a of the flexible sill strip 12, said bead yielding sufficiently to accommodate the entry of the sash strip while holding the free edge thereof in contact with the inner flange of said rigid strip. In this construction, the sill strips 11 and 12 are applied to the sill directly and with-

out any alteration of the sill; but as the sill strip projects above the sill, the outer bottom portion of the sash B is rabbeted in order that the loop of the sash strip 13 secured to the bottom of the sash may be located at the same height with the raised portion of the rigid sill strip.

The sill joint, formed by the cooperating portions of the sash or door member, the rigid sill strip and the flexible sill strip, remains waterproof under normal conditions by reason of the three lines of contact between said members. The walls of the pocket portion of the flexible door strip press resiliently upon both sides of the rigid sill strip and thus form two lines of contact; and the free edge of the pocket of said flexible sash or door strip enters between the rigid sill strip and the flexible sill strip whereby a third line of contact is formed, namely between the lower portion of the flexible sash or door strip and the upper portion of the flexible sill strip.

The space between the side rails of the sash B and the sides C of the window frame are weatherproofed by any suitable weather strip, but such strip should be located outwardly with relation to the sill strip; that is, the side strip should be so located that the water draining therefrom should be delivered outside of the sill joint. In the construction illustrated in Figs. 1 and 2, the side strip comprises a wide strip 14 of sheet metal whose marginal portions are doubled and which is folded lengthwise near the middle thereof. A fold is made in the form of a tubular bead 14^a, and the two body portions lie at a considerable inclination to each other. In practice, the side strip is located between the side of the window frame and the sash therein, and is nailed or otherwise secured along one outer margin of the window frame, the other margin being free and adapted to bear resiliently against the side of the casement sash, when the same is closed. As suggested above, the vertical plane of the bead 14^a of the side strip 14 is located outwardly with relation to the vertical web of the sill strip 11, so that any water that may flow downwardly along said side strip will be delivered into the trough formed by the hollow bead 12^a of the flexible sill strip 12 and flow through the outlets 11^a onto the sill outside of the weatherproofing joint therefor.

One of the great advantages of the foregoing construction is that it is not only waterproof under normal conditions but that it remains waterproof against hard rains and driving winds. Under such conditions, there is a tendency for water to "pile up" on a sill and be forced through the weatherproofing devices. With my construction, however, the force of the wind is broken by the vertical member of the sill

strip, that constitutes a wind break or shield, so that the space back of said wind break is comparatively free from the force of the elements. Any water that may be forced in between the sash strip and the rigid sill strip will be delivered into this comparatively quiet space between the rigid and the resilient strips of the sill member, from which it will pass out through the weep holes provided therefor as quickly as conditions permit.

In the construction illustrated in Fig. 4, the space between the hinged side of the sash and the window frame is weatherproofed by means of cooperating bead and groove strips of substantially V-shaped section. The bead strip 15 is secured to the window frame and the groove strip is secured within a vertical rabbet formed in the outer edge of the sash in position to straddle or embrace the rib strip in the closed position of the sash. These strips are located outwardly with relation to the sill strip so that water draining therefrom is delivered outside of such sill strip.

In the construction illustrated in Fig. 5, the invention is shown applied to a door. In this construction the sill member comprises a rigid threshold plate 16 and a flexible sill strip 17. The plate 16 is fastened to the sill and has an inwardly projecting horizontal flange 16^a spaced above the sill and at such height to be straddled by the loop of the door strip 18 in the closed position of the door. The flexible sill strip 17 is located beneath the plate 16 and has a hollow bead 17^a located beneath the overhanging flange 16^a of the plate 16. The hollow bead 17^a at the inner margin of the flexible sill strip 17 is protected against crushing by means of a separate base strip 19 having a flat body portion located beneath the inner marginal portion of the strip 17 and having a rib 19^a located outside of the beaded portion of said strip. The threshold plate 16 is provided with aligned weep holes 16^b so that any water delivered to the space between the rigid and resilient strips of the sill member will pass out through said weep holes.

In the construction illustrated in Fig. 6, a rigid door-sill plate 20 has an overhanging flange 20^a adapted to be engaged by the loop of the door strip 21. A flexible sill strip 22 is located between the door sill plate and door sill and has an upwardly inclined beaded outer margin 22^a adapted to bear against the loop of the door strip in the closed position of the door. The door sill plate 20 is provided with suitable weep holes 20^b adapted to deliver water from the space formed by the cooperating inner marginal portions to the outer side of the door sill.

The construction illustrated in Fig. 7 is similar to the construction illustrated in Fig.

6, except for a slight difference in the shape of the flexible sill strip, the sill strip 23 shown in Fig. 7 having its inner marginal portion doubled back in the form of a loop 5 23^a which engages the under side of the loop of the flexible door strip.

In the construction illustrated in Fig. 8, the invention is shown in connection with a casement window. In this construction, the 10 rigid sill strip is shown in the form of a channel strip 24 whose inner wall is provided at its upper edge with an inwardly extending horizontal flange 24^a. This flange is adapted to be embraced by the loop portion of the flexible sash strip 25 in the closed position of the sash; and the doubled under portion of said loop is adapted to engage the hollow bead 26^a of a flexible sill strip 26, whose flat portion is clasped between the 15 rigid sill strip 24 and the sill. The rigid sill strip is provided with suitable outlets 24^b for draining water from the beaded portion of the flexible sill strip onto the outer portion of the sill.

25 The arrangement shown in Fig. 9 is similar to that shown in Fig. 8, except that the channel shaped sill strip 27 of Fig. 9 differs from the sill strip of Fig. 8 by having its bottom spaced above the flat portion of the 30 flexible strip by means of depending side flanges 27^a. These flanges are provided with alined weep holes 27^b for draining the water from the space formed by the inner side of the rigid sill strip and the beaded portion 35 of the flexible sill strip.

In the construction illustrated in Fig. 10, the rigid sill strip is shown in the form of a flat plate 28 which is secured to the stool D of the sill. This plate overhangs the inner edge of the stool and is adapted to be engaged by the loop portion of the flexible sash strip 29 in the closed position of the sash. The flexible sill strip is shown in the form of a strip 30 of Z-shaped section fitted 40 in the angle between the sill and stool, the top flange of said strip resting on the stool beneath the rigid strip 28 and the bottom flange being curled upwardly and backwardly to form a hollow bead 30^a underneath 45 the overhanging portion of the rigid sill strip 28. The stool and the vertical web of the flexible sill strip are provided with registering weep holes 31 for conducting water from the beaded portion of said flexible strip 50 to the outer portion of the sill.

55 Among the advantages of my invention is the facility with which it may be applied. In all cases, the two parts forming the sill member may be applied directly without any 60 alteration of the sill; and the only alteration required to be made in the bottom rail to accommodate the resilient strip therefor is to rabbet or groove the outer bottom edge thereof. Likewise, the side strip is very easy 65 of application; as it is merely necessary to

swing open the casement or door and nail the side strip to the side of the frame. In addition to this, the device has the further advantage of being very easy to make and any broken or worn parts may be very quickly and easily replaced.

70 Obviously, the invention is not limited to the particular window and door construction and the side and bottom strips shown and described.

75 What I claim is:

1. A sill member for weatherstrips comprising a relatively rigid strip having a flat marginal portion and a relatively flexible strip having an open tubular portion underneath and normally yieldably engaged with said flat portion, substantially as described.

80 2. A structure having a sill member for weatherstrips comprising a relatively rigid strip having a marginal portion spaced above the sill, and a relatively flexible strip secured flatwise to the sill underneath said rigid strip and having a margin curled upwardly and backwardly underneath and normally yieldably engaged with said marginal portion of said rigid strip.

85 3. In a weather strip, a sill member comprising a relatively rigid strip having a marginal portion adapted to be spaced above the sill, and a relatively flexible strip adapted to be secured flatwise to the sill underneath said rigid strip and having a free marginal portion underneath said marginal portion of said rigid strip and yieldable relative thereto, and a sash member comprising a strip adapted to be secured to the bottom of a swinging sash and having a marginal loop in position for said rigid strip to enter when the sash is closed said free marginal portion of said flexible strip serving to yieldably hold the marginal loop of said sash strip in contact with said rigid sill strip.

90 4. A sill member for weatherstrips comprising a flexible strip having an upwardly and backwardly curled margin and a rigid strip superposed on said first strip and having its own margin above and normally in contact with said curled margin of said first mentioned strip.

95 5. A sill member for weather strips comprising a strip having an upwardly and backwardly curled margin and a second strip superposed on said first strip and having its own margin above and in yielding contact with said curled margin of said first mentioned strip, said member having provision for draining the space in said curled margin.

100 6. The combination, with a closure and the frame therefor, of weather proofing means comprising side strips and interengaging bottom strips, said bottom strips cooperating to form a trough, said side strips being located outwardly with relation to the

- vertical plane of the bottom strips so that any water that runs down said side strips will be delivered into the trough formed by said bottom strips. 35
- 5 7. In a construction of the kind set forth the combination of a sill having a relatively rigid member thereon and a resilient member beneath said rigid member and normally in yielding contact therewith, of a closure 40
10 having a member secured to the bottom thereof and provided with a loop adapted to straddle said rigid member and to be held in yielding contact therewith by said resilient member.
- 15 8. In a construction of the kind set forth the combination of a sill having a relatively rigid member thereon and a resilient member beneath said rigid member and adapted 45
20 to yieldably engage a portion of the under surface thereof, of a closure having a member secured thereto and provided with a free 50 marginal portion adapted to enter between the engaged surfaces of said rigid member 55 and said resilient member.
- 25 9. The combination with a closure and the sill therefor, of a relatively rigid strip secured to said sill and having a marginal portion spaced therefrom, a resilient strip 60
30 secured to said sill and having an upwardly and backwardly curled marginal portion located beneath said marginal portion of said rigid strip and adapted to engage therewith when the closure is in the open position, and
- a member secured to said closure and adapted in the closed position thereof to extend across the spaced marginal portion of said rigid strip and enter between said portion and the curled marginal portion of the resilient strip engaged therewith. 65
10. The combination with a closure and the sill therefor, of a relatively rigid strip secured to said sill and having a marginal portion spaced therefrom, a resilient strip secured to said sill and having an upwardly and backwardly curled marginal portion located beneath said marginal portion of said rigid strip and adapted to engage therewith when the closure is in the open position, and a member secured to said closure and adapted in the closed position thereof to extend across the spaced marginal portion of said rigid strip and enter between said portion and the curled marginal portion of the resilient strip engaged therewith, said rigid member having provision for draining the space within said curled margin. 70
11. A sill member for weather strips comprising a relatively rigid member having a raised marginal portion, and a resilient member having a free marginal portion underneath said raised marginal portion and yieldable relative thereto. 75

Signed at St. Louis, Missouri, this 1st day of March, 1922.

ALFRED M. LANE.
